UNITED STATES PATENT OFFICE.

DAVID G. McCAA, OF LANCASTER, PENNSYLVANIA.

HIGH-FREQUENCY GENERATING SYSTEM.

1,360,126.

Specification of Letters Patent. Patented Nov. 23, 1920.

Application filed May 26, 1917. Serial No. 171,179.

To all whom it may concern:

Be it known that I, DAVID G. McCAA, a citizen of the United States, residing in the city and county of Lancaster, State of Pennsylvania, have invented High-Frequency Generating Systems, of which the following is a specification.

This invention relates to apparatus for the production of sustained or continuous oscillatory currents of high frequency, such as are used in the art of signaling by electromagnetic waves.

One object of the invention is to provide a simple, durable and easily operated combination or system of apparatus whereby it shall be possible to convert a single phase alternating current, such as that supplied from commercial lighting mains, into continuous high frequency oscillations of uniform power, for use in radio telegraphy and telephony.

It is further desired to provide a system of the general type above noted which shall be positive and relatively stable in action, of such a nature as shall not require adjustment when in action and from which it shall be possible to obtain currents having a wide range of frequencies.

These objects and other advantageous ends 30 I secure as hereinafter set forth, reference being had to the accompanying drawings, in which,

Figure 1 is a diagrammatic view illustrating a system of apparatus for producing sustained oscillations in a radiating circuit and in which the various parts are arranged and connected in accordance with my invention; and

Fig. 2 is a diagrammatic view illustrating the phase relations of the low frequency currents in certain parts of the system and also illustrating the type of primary and secondary high frequency oscillations as well as their relation, as regards power, to 45 said low frequency current.

In Fig. 1 of the above drawings, 1 represents a source of alternating current such as an alternator of any definite frequency ranging for example, from twenty-five to two 50 thousand cycles, or it may be the mains of a commercial lighting system in which a

sixty cycle current is supplied at a pressure of one hundred and fifteen volts.

Connected to this source in parallel with each other are two circuits A and B, and of these the first includes a device 2 for making and breaking the current flow in said circuit, a condenser 3 and the primary winding 4 of a transformer 5. The secondary winding 6 of said transformer is connected in circuit with two condensers 7 and 8, and the latter condenser also forms part of a circuit including a quenched spark gap 9 and the primary winding 10 of a high frequency transformer. The secondary winding 11 of this transformer is connected in a circuit 12 which includes the antenna 13, the winding 14 of a second high frequency transformer, and a ground connection 15.

The second main circuit B includes a device 16 for making and breaking the current flow, a reactance coil 17 and the primary winding 18 of a transformer 19. The secondary winding 20 of this transformer is connected in circuit with a second reactance 75 coil 21 and with a condenser 22, while the latter has in shunt to it a quenched spark gap 23 and the primary winding 24 of the second high frequency transformer, whose secondary is connected in the antenna circuit 12.

The circuits 8—9—10 and 22—23—24, are preferably designed to have equal capacities 8 and 22, equal inductances 10 and 24, and the same gap conditions, although this uniformity is not absolutely essential to the successful operation of my invention and I do not limit myself to such construction. These two circuits constitute the primary high frequency oscillatory systems which supply the 90 secondary or antenna systems 13—11—14—15 and maintain it in continuous oscillation under operating conditions. The function of the remainder of the apparatus is to supply to the condensers 8 and 22, low 95 frequency high tension currents which are of equal power and which are properly controlled as to the amount of power and properly spaced as regards their time relation.

In an oscillatory circuit such as that provided by the elements 8—9—10 or 22—23—24, it is possible, by properly adjusting the

capacity, the length and number of the spark gaps, and the supply current, to obtain highly damped discharges at exceedingly high group frequencies. The damping is independent of any reaction by a secondary circuit and the action of the discharges in the secondary circuit assumes a type of impulse excitation. Group frequencies of from twenty to forty thousand impulses a second are obtainable and as the primary discharges occur throughout the major portion of each alternation of the low frequency high tension charging current, continuous oscillations are produced in the secondary circuit when this is coupled to the primary circuit or system operating as above described, throughout the major portion of the time of each low frequency alternation, provided the decrement of the oscillations in said secondary circuit is not too high.

For efficient operation the supply current must be properly controlled, and this can be accomplished by the introduction of capacity, resistance, or inductance, in either the primary or secondary, or in both the primary and the secondary circuits, of the supplying transformer. In this case, capacity operates as a capacity reactance determinable by the formula $\frac{1}{2\pi NJ}$, in which N is the frequency and J is the capacity. Inductance operates as magnetic reactance and is determined by the formula $2\pi NL$. Both the capacity and inductance operate in a manner similar to resistance and limit the current flow.

The condensers 3 and 7 in the circuit A and the reactance coils 17 and 21 of the circuit B are so designed relatively to the transformer windings 4 and 6 on the one hand and to the windings 18 and 20 on the other, as to permit the same currents to flow to charge the condensers 8 and 22. With the arrangement of circuits shown in Fig. 1, the current flowing to and charging the condenser 8 will be out of phase with the current flowing to and charging the condenser 22 as would not be the case if resistance was employed to control or limit the current flow to said condensers, for the capacity provided in circuit A by the condensers 3 and 7, causes the current in this circuit to lead the impressed electro-motive force, while the inductance provided by the coils 17 and 21 in circuit B, causes the current in the latter to lag behind the impressed electro-motive force. In both circuits the inductance of the primary and secondary windings of the transformers 5 and 19, is balanced against the capacity of the condensers 8 and 22.

In order to obtain the proper time relation between the currents supplied to the con-

densers 8 and 22, it is essential that the sum of the increase of the angle of lag and of the increase of the angle of lead, shall be equal to 90° . This phase relation is illustrated in Fig. 2, in which the line 25, with ordinates above and below the abscissa 26 (which represents time), represents the impressed electro-motive force and current of the supply 1, assuming these to be in phase. The curved line 27 similarly represents the current leading the impressed electro-motive force by an angle of 45° ;—the distance from the vertical line 28 to the parallel line 29 being equal to one-fourth of one alternation. The curved line 30 represents the current lagging behind the impressed electro-motive force by an angle of 45° , the distance from the line 29 to the line 31 being equal to one-fourth of one alternation. Obviously therefore the currents represented by the lines 27 and 30 are 90° apart, are at right angles or in quadrature to each other and therefore in quarter or two phase relation.

While the impressed electro-motive force of the source and the current supplied are usually not in phase, this condition will not interfere with the operation of the system, since suitably selected capacities and reactances may be employed to advance or retard the current as required, until the desired 90° phase difference is obtained. As will be understood by those skilled in the art, it is not necessary that the current in one circuit shall be advanced 45° and the other retarded the remaining 45° as indicated in Fig. 2, since any angle of lead and any angle of lag may be employed provided the sum of the two angles equals 90° .

Since the leading effect of capacity and the lag effect of inductance are decreased by resistance, it is preferable to keep the ohmic resistance of the circuits relatively low.

As indicated in Fig. 2, the condenser 8 will discharge as described during the time period of the alternations of its supply current, the highly damped primary discharges induced by the current indicated by the line 27 being represented at 32 and their power by the varying ordinates of said line. Similarly the variations in the discharges resulting from the current flow indicated by the line 27, are illustrated by 33.

The oscillatory primary impulses excite the secondary or antenna circuit by shock or impulse excitation and permit it to oscillate in its own natural period during the time intervals between the primary discharges. From the relation of the primary discharges as regards the power indicated by the ordinates of the oscillations 32 and 33, it will be seen that power is supplied to the antenna at a uniform rate and that as indicated at 34, the antenna oscillations are continuous owing to the overlapping of the

primary discharges and the balancing of the power supplied to the two circuits. The line 34 therefore represents the secondary or antenna oscillations and its ordinates are 5 all equal, by reason of the quarter phase relation and of the above described adjustment of the current flow in the primary oscillatory systems 8—9—10 and 22—23—24.

I claim:—

- 10 1. A generator for continuous high frequency oscillations comprising a source of single phase alternating current; two circuits connected thereto and each including a primary high frequency oscillatory quenched 15 gap system; a secondary high frequency oscillatory system coupled to both of said primary systems; and means for causing a phase difference of 90° in the currents of said primary systems.
- 15 2. The combination of an antenna system; two high frequency oscillatory systems coupled to said antenna system; and means for maintaining continuous high frequency oscillations in the antenna system including 20 means for supplying to said oscillatory systems low frequency high tension currents having a phase difference of 90°.
- 25 3. The combination of a source of single phase current; two low frequency high tension circuits supplied therefrom; means for causing the current in one circuit to lead the impressed electro-motive force; means for causing the current in the other circuit to lag behind the impressed electro-motive 30 force; primary high frequency oscillatory systems actuated from said low frequency systems and comprising a quenched spark gap; and a secondary high frequency oscillatory system coupled to both of said primary high frequency systems.
- 35 4. A generator for continuous high frequency oscillations comprising a source of single phase current; two low frequency high tension systems operatively connected 40 to said current source and including means whereby the currents flowing in them are caused to have a phase difference of 90°; primary high frequency oscillatory systems operatively associated with said low frequency systems and including quenched 45 spark gaps; and a secondary high frequency oscillatory system coupled to both of said primary systems.
- 50 5. A generator for continuous high frequency oscillations comprising a source of single phase current; two low frequency high tension systems supplied therefrom; a capacity for causing a leading current in one of said systems; a reactance for causing a lagging current in the other system; primary high frequency oscillatory systems 55 respectively associated with said low frequency systems and including quenched spark gaps; and a secondary high frequency oscillatory system coupled to both of said primary systems.
- 60 6. A generator for continuous high frequency oscillations comprising a source of single phase current; two low frequency high tension systems supplied therefrom; a capacity for causing a leading current in one of said systems; a reactance for causing a lagging current in the other system; primary high frequency oscillatory systems 65 respectively associated with said low frequency systems and including quenched spark gaps; and a secondary high frequency oscillatory system coupled to both of said primary systems.

frequency oscillatory system operatively associated with said primary systems. 65

6. A generator for continuous high frequency oscillations comprising a source of single phase alternating current; two circuits connected in parallel to said source; a condenser in one of said circuits; a reactance in the other circuit; two transformers having their primary windings respectively connected in said circuits; condensers connected in circuit with the secondary windings of the transformers respectively; a quenched spark gap and the primary winding of a high frequency transformer in circuit with each of said latter condensers; and an antenna circuit including two secondary 70 high frequency transformer windings respectively associated with said high frequency primary windings. 75

7. The combination of a source of alternating current; two circuits connected in parallel therewith; two transformers having their primary windings respectively connected in said two circuits; two condensers in circuit with the secondary winding of one of said transformers; a condenser and a reactance in circuit with the secondary winding of the other transformer; two high frequency transformers; spark gaps respectively connected in circuit with the primary windings of said high frequency transformers and with one of the condensers of said circuits; and an antenna connected in circuit with the two secondary windings of said high frequency transformers. 90 95

8. The combination of a source of alternating current; two primary high frequency oscillatory systems connected in parallel to said source; a secondary high frequency oscillatory system coupled to both of said primary systems; and means for controlling the amounts of power supplied to the primary oscillatory systems, consisting of capacity in one of said primary systems and inductance in the other primary system. 100 105

9. A generator for continuous high frequency oscillations comprising a source of single phase alternating current; two primary high frequency oscillatory systems connected in parallel to said source and including quenched spark gaps; a secondary 110 high frequency oscillatory system coupled to both of said primary systems; and means for controlling the amounts of power supplied to the primary oscillatory systems, said apparatus being adjusted to maintain a phase 115 difference of 90° between the currents in the primary oscillatory systems. 120

10. The combination of a source of alternating current; two primary high frequency oscillatory systems connected to said source in parallel with each other; an antenna system operatively coupled to both of said oscillatory systems; with means for control- 125

ling said latter systems consisting of capacity reactance in one of them and magnetic reactance in the other.

11. The combination of a source of alternating current; two primary high frequency oscillatory systems connected to said source in parallel with each other; an antenna system operatively coupled to both of said oscillatory systems; with means for control-

ling said latter systems consisting of capacity reactance in one of them and magnetic reactance in the other, said primary oscillatory systems being adjusted to cause a phase difference of 90° between the currents flowing therein. 10

15. In witness whereof I affix my signature.

DAVID G. McCAA.
